VALVE RESEATER

Martin Nathan Kaplan, 11610 Cantlay St.,
North Hollywood, Calif. 91605

Filed May 19, 1972, Ser. No. 255,307

Term of patent 14 years

Int. Cl. D8—05

U.S. Cl. D8—59

FIG. 1 is a top perspective view of a valve reseater showing my new design;

FIG. 2 is a front elevational view thereof with an element in an alternate position; and

FIG. 3 is a rear elevational view thereof with the element in a further alternate position.

I claim:

The ornamental design for a valve reseater, as shown and described.
